UNITED STATES PATENT OFFICE.

MOSE EDWARD BAKER, OF DES MOINES, IOWA.

JIG SAW.

Application filed June 18, 1923. Serial No. 646,075.

To all whom it may concern:

Be it known that I, MOSE EDWARD BAKER, a citizen of the United States, and a resident of Des Moines, in the county of Polk and 5 State of Iowa, have invented a certain new and useful Jig Saw, of which the following is a specification.

The purpose of my invention is to provide a simple and inexpensive jig saw structure.

More particularly, it is my object to provide a jig saw, which is very light and is so constructed that it can be easily moved from place to place and can be readily 10 mounted on a bench or other support wherever desired.

One of my purposes in constructing my jig saw is to provide such a saw so arranged that it can be fastened by means of clamps 20 on a bench or the like, and is very compact, so that I avoid the necessity of providing a three or four legged stand to support it.

Still another object is to provide such a structure having a foot pedal and spring 25 device for operating the saw, parts being so arranged that adjustment can be readily made for placing the work table at any desired height. This feature of construction is important because my jig saw is designed, 30 among other things, for use in school and the same jig saw can thus be conveniently used by children of different grades.

With these and other objects in view, my invention consists in the construction, arrangement and combination of the various 35 parts of my device, whereby the objects contemplated are attained, as hereinafter more fully set forth, pointed out in my claims, and illustrated in the accompanying drawings, in which:

Figure 1 shows a side elevation of a jig saw embodying my invention installed on a work bench.

Figure 2 shows a front elevation of the 45 same.

Figure 3 shows a vertical, detail, sectional view taken on the line 3—3 of Figure 1.

Figure 4 shows a perspective view of the 50 frame of my device, parts being broken away.

Figure 5 shows a perspective view of a means for securing different saws to the saw arms; and

Figure 6 shows a sectional view taken on 55 the line 6—6 of Figure 1.

One feature of my improved jig saw lies in the arrangement wherein a frame is provided in which all the parts are supported from a single horizontal member, which member is provided with clamps, whereby 60 it may be readily mounted on a work bench.

In the accompanying drawings, I have used the reference numeral 10 to indicate generally such horizontal member, which may be in the form of a board arranged as 65 shown in the drawings.

Secured to what may be called the rear end of the horizontal member 10 is an upright 11, which projects above and below the member 10.

The frame of the device, I preferably make of wood and the members are preferably connected together by bolts 12, so that the frame can be readily taken apart or reassembled.

Supported on the upper edge of the horizontal member 10 at its front portion is a board 13 forming a table.

A bracket or brackets 14 may be connected with the member 10 for rigidly holding the 80 table 13 in place.

Pivoted to the upright 11 below the level of the table 13 is a lower saw arm 15, which projects slightly rearwardly beyond the upright 11.

Above the table 13 is an upper saw arm 16, which is pivoted on the upright 11. The saw arms may be pivoted on bolts 16^a and supported by brackets 16^b.

Extra holes 17 are provided in the upright 90 11 for pivoting the saw arms at different points for using saws of different lengths for cutting different stock on the device.

A saw 18 is mounted in the front ends of 95 the saw arms 15 and 16 and extends through a suitable hole 19 in the table 13.

The rearwardly projecting ends of the saw arms are adjustably connected by some suitable means. For illustrative purposes, 100 I have shown the turn buckle structure 20. A great variety of means might accomplish this purpose and be readily substituted for the turn buckle shown.

Extended forwardly from the upright 105 11 below the horizontal member 10 is a shorter horizontal member 21.

A brace element 22 is secured to the member 21 forwardly with relation to the upright 11 and inclines upwardly to and is se- 110

cured to the horizontal member 10 and also serves as a support for the table 13, as shown in Figure 1.

Secured to the under side of the table 13 and to the brace member 22 is a bracket 23, which has adjacent to the brace member 22 a slot 24, which receives the lower saw arm 15 so that the member 22 and the bracket 23 form guides for the lower saw arm.

Secured to the rear portion of the horizontal member 10 and inclining upwardly and forwardly therefrom is a spring support 25, which overhangs the saw arms and has at its upper part spaced angle iron bracket devices 26 to receive and support a coil spring 27, which spring is also secured to the upper saw arm 16.

Different brackets 26 are provided for affording points of attachment for the spring at different heights, so that the spring may be operative when the saw arms are adjusted for using saws of different lengths.

Secured to the horizontal frame member 10 are spaced clamp devices 28 and 29 for mounting the frame of my jig saw on a work bench 30 or the like.

It will be seen that the frame heretofore described can be readily and easily mounted on a bench.

Where benches of different heights are used in schools to accommodate children of different grades or of different sizes, it will be seen that my jig saw structure can be mounted on any of such benches.

In order to accomplish this purpose, I have provided a structure in which I have done away with the use of supporting frames and legs.

It is my purpose to operate the jig saw by foot power and having this purpose in mind and desiring also to provide for the ready mounting of the frame on benches or desks of different heights, it is necessary to provide a foot pedal structure capable of being secured near any bench and of having adjustable connection with the saw arms.

For this purpose, I have provided a bracket 31 which can be readily and easily secured by bolts or screws 32 to a floor. Pivoted to the bracket 31 is a foot pedal 33. A rope or other flexible device 34 connects the pivoted foot pedal member 33 with the lower saw arm 15. This flexible element can, of course, be readily adjustable for operating the jig saw at different heights.

It will be readily seen that my jig saw structure is of very simple and inexpensive construction and is particularly adapted for use in manual training in schools.

I have some of them in use even in the kindergartens and can readily mount them on the kindergarten tables or on higher benches or tables.

The jig saw device herein described is not only readily adaptable for children of dif-

ferent sizes, but has a considerable range of usefulness, because of its structural features to which attention has already been called.

It will be noted that the arm 15 is preferably located closer to the table 13 than the arm 16, so that the saw will be inoperative on the up stroke and the spring will readily carry it upwardly.

In order to make it easy to install saw blades of different lengths and thicknesses, I have formed each saw arm with a slot 25 in its end wide enough to take care of the thickest saw blade that will be employed.

Pivoted to the upper surface of the upper saw arm and to the lower surface of the lower saw arm is a plate 26, which is pivoted between its ends by means of a pivot member extended through the hole 27.

In the ends of the plates 26 are slots 28 and 29 adapted to receive saw blades of different thicknesses, and across the outer face of each plate are grooves 30 to receive a pin extended through the saw blade.

It will be seen that by loosening the turn-buckle 20 or other means used for the purpose, the saw blade may be removed and another saw blade inserted in its place, after the plates 26 have been turned around.

The saw arms can be adjusted on the upright 11 for sawing thicker stock, after a longer saw has been assembled on them, and the spring 27 can be supported from the upper or lower brackets 26 as may be desired.

Some changes may be made in the construction and arrangement of the various parts of my improved jig saw without departing from the real spirit and purpose of my invention, and it is my intention to cover by my claims, any modified forms of structure or use of mechanical equivalents, which may be reasonably included within their scope.

I claim as my invention:

1. A portable jig saw comprising an upright arm, a horizontal arm projecting therefrom, a table on said horizontal arm having a hole therethrough, a pair of saw supporting arms pivoted to said upright arm, a saw mounted between the ends of said saw supporting arms, adjustable means for connecting the opposite ends of the saw supporting arms, an inclined arm extending upwardly from said horizontal arm, a coil spring connected with the upper saw supporting arm and with said inclined arm, a bracket, a foot pedal pivoted to said bracket and a flexible member connecting the foot pedal and the lower saw supporting arm, a second horizontal arm spaced from the first, a guide for the lower saw arm supported on said horizontal arms.

2. A portable jig saw comprising an upright arm, a horizontal arm projecting therefrom, a table on said horizontal arm

having a hole therethrough, a pair of saw supporting arms pivoted to said upright arm, a saw mounted between the ends of said saw supporting arms, adjustable means 5 for connecting the opposite ends of the saw supporting arms, an inclined arm extending upwardly from said horizontal arm, a coil spring connected with the upper saw supporting arm and with said inclined arm, a 10 bracket, a foot pedal pivoted to said bracket

and a flexible member connecting the foot pedal and the lower saw supporting arm, a second horizontal arm spaced from the first, a guide for the lower saw supporting arm, a second horizontal arm spaced from the 15 first, a guide for the lower saw arm supported on said horizontal arms, and serving also as a support for said table.

Des Moines, Iowa, April 6, 1923.
MOSE EDWARD BAKER.
